UNITED STATES PATENT OFFICE.

ELBERT H. CARROLL, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

MEANS FOR SECURING BLADES IN SHEARING-MACHINES.

1,146,475.

Specification of Letters Patent.

Patented July 13, 1915.

Application filed November 27, 1912. Serial No. 733,731.

To all whom it may concern:

Be it known that I, ELBERT H. CARROLL, a citizen of the United States, residing at Worcester, in the county of Worcester and 5 Commonwealth of Massachusetts, have invented a new and useful Improvement in Means for Securing Blades in Shearing-Machines, of which the following, together with the accompanying drawing, is a specification.

10 My invention relates to shearing machines and more particularly to improved means for securing a shear blade in operative position in a machine of that class.

15 An object of the invention is to secure a shear blade in operative position by means so constructed and arranged that the blade may be very easily and quickly removed from the machine.

20 Another object of the invention is to provide means for securing a shear blade in position, not only in the line of relative motion of the blades, but which shall at the same time resist lateral thrust such as might 25 be exerted by another blade.

Further advantages will be apparent from the following description in connection with the accompanying drawing showing one embodiment thereof, and in which—

30 Figure 1 is a partial view of a shearing machine looking toward the ends of the blades, the machine being of a type suitable for cutting metal bars; Fig. 2 is a view of the same portion of the machine shown in 35 Fig. 1, but looking toward the sides of the blades; and Fig. 3 is a view similar to Fig. 1 except that a portion of the view is in section on the line 3—3 of Fig. 2.

Similar reference characters refer to similar parts in the different figures.

40 The machine shown in the drawing is of a type commonly used for cutting metal bars and rods and includes two coöperating shear blades 1 and 2. The upper blade 1 is mounted in any suitable manner upon a reciprocating plunger 3, the plunger being operated by any suitable means to cause the blades to open and close. The principle of my invention is disclosed in the means 45 shown for mounting the lower blade 2. This blade 2 is secured by bolts 4 to a block or support 5, which is recessed along one edge to fit the blade and afford a proper support therefor. The block 5 has on its

lower face a longitudinal rib 6 and a transverse rib 7, both rectangular in cross section, and these ribs fit in corresponding grooves shaped to fit and receive the ribs and formed in the upper surface of a base 8 of the machine. It is clear that these ribs 55 and grooves will coöperate to resist effectively all forces tending to produce lateral or longitudinal movement of the block 5 and blade 2. It is customary to provide, in machines of this type, a support for the lower 60 blade similar to the block 5, but such support has been previously secured to its seat by bolts passing directly down into the base of the machine. In accordance with my invention, I secure the block 5 to its seat by 65 bolts 9, which are placed at substantially right angles to a plane extending from the cutting edge of the lower shear blade 2 to an axial line about which the shearing strain tends to impart a rotative moment, 70 which becomes considerable when the cutting corner of the lower shear blade becomes rounded by continued use. The axial line, in the present instance, is located at the contact of the base 8 with the rear edge of the 75 block 5. By placing the bolts 9 at substantially right angles to the broken line 9^a, indicating the plane connecting the corner of the blade 2 and the rear corner of the block 5, the maximum resistance is exerted to the 80 rotative moment of the block 5 and the latter is securely held from being lifted from the base 8. In other words, the pressure of the movable blade 1 during the shearing operation tending to rock the blade 2 and support 5 upon the frame, is exerted through a lever arm coinciding in length and direction with the line 9^a, and the bolts 9 are 85 so disposed as to exert the maximum resistance to this turning movement. The 90 bolts 9 are headed at their upper ends and are secured in position by driving small wedges 10 through transverse openings in their lower ends.

To facilitate removal of the block 5 with 100 the lower blade 2, the openings provided for the bolts 9 in the base of the machine are extended laterally forming slots 9^b, obviating the necessity of withdrawing the bolts 9 longitudinally to remove them, it being 105 necessary only to remove the wedges 10 and lift the bolts out of the slots 9^b in removing the block 5 and blade 2.

I do not wish to be limited to the exact details of construction shown and described, as various changes may be made within the scope of the appended claims without departing from the spirit of the invention; but

Having described my invention, what I claim as new and desire to secure by Letters Patent is:

1. A shear including a pair of coöperating blades, a support upon which one of the blades is mounted, and a bolt securing said support to the frame of the shear, said bolt extending at an oblique angle to the line of motion of the movable blade.
2. A shear including a pair of coöperating blades, and means for securing one of said blades to the frame of the shear, comprising a bolt extending at an oblique angle to the line of motion of the movable blade.
3. A shear including a pair of coöperating blades, and means for securing one of said blades to the frame of the shear, comprising a bolt extending substantially at right angles to a plane coincident with the lever arm through which the strain of the cutting operation is exerted, to rock said blade about said frame.
4. A shear including a pair of coöperating blades, a member upon which one of said blades is mounted, said member having an extended supporting surface upon the frame of the machine, and a bolt securing said support to said frame, said bolt ex-

tending substantially at right angles to a line connecting the edge of said blade with the remote edge of said supporting surface.

5. A shear including a pair of coöperating blades, a member carrying one of said blades at its end, and having an extended supporting surface upon the frame of the shear, and a bolt securing said member to the frame, said bolt extending substantially at right angles to the plane connecting the edge of said blade with the remote edge of said supporting surface.

6. A shear including a pair of coöperating blades, a support upon which one of the blades is mounted, the support and the frame of the shear having a rib and groove connection, and a bolt attaching said support to said frame and extending at an oblique angle to the ribbed and grooved surfaces.

7. In a shear of the class described, comprising a pair of coöperating blades, a base, a block supported on said base, a shear blade attached to said block, and a bolt attaching said block to said base, with the axis of said bolt at substantially right angles to a plane including the cutting edge of the shear blade and the axis about which the rotative moment of shearing is exerted.

Dated this 22nd day of November, 1912.

ELBERT H. CARROLL.
